ABSTRACT: A chemical-mechanical timing device for automatically releasing a retained member at the end of a predetermined period of time. The apparatus includes a chemical pellet, and associated rivet, which are kept dry until the timing action is to begin. Then the pellet is exposed to the moisture in the ambient air, or water for underwater devices, and a chemical action is initiated between the pellet and rivet. The rivet is partially consumed and weakened to the point of releasing a retained member.

Robert P. Gibson

ATTORNEYS

CHEMO-MECHANICAL TIMER

BRIEF SUMMARY

In many instances it is desirable to automatically actuate a mechanical device after a certain delay period. As an example, several hours or several days after apparatus is exposed to atmospheric conditions, where water vapor is present, it may be desirable to release a spring-driven device, turn on a switch, or such. As another example, it may be desirable to actuate such apparatus several minutes, several hours or several days after the apparatus is thrown overboard from a boat or dropped into a body of water.

The present invention performs such functions. The moisture entering the apparatus initiates a reaction in a pellet, of a corrosive salt for example. The corrosive salt attacks an element of the apparatus, such as an aluminum rivet for example. The element is progressively weakened to the point where it can no longer restrain a part and "lets go."

It is an object of this invention to provide a chemical-mechanical timing device as set out above which is simple in operation, inexpensive to mass-produce, reliable in operation, small in size and light in weight. Such device has no springs or such energy sources, or gear trains or similar mechanical parts. In the drawing:

FIG. 1 is a view of the invention in partial cross section;

FIG. 2 is an exploded view of the invention.

Body member 1 is provided with a recess 2 to receive the basic components of the invention. The basic parts, including rivet 4, hold a mechanical coupling or securing member 3 fixed to body 1. The components comprise a rivet or other securing device 4, a pellet 5, a membrane 6 and a retainer 7 having moisture access holes 8 therein. Moisture from the surrounding environment enters through holes 8 in retainer 7, penetrates membrane 6, and softens or dissolves pellet 5. Pellet 5, of cupric chloride salt for example, is corrosive with respect to rivet 4 which may be made of an aluminum alloy for example.

OPERATION

When the quantity of water or vapor entering the cavity has reached a critical value the pellet constituents initiate a gas phase chemical reaction with the metal rivet. The gas phase reaction forms reaction products which are very hygroscopic, hence a small bubble is formed on the rivet head. The bubble grows until it closes the gap between the rivet head and the pellet. When the bubble attaches to the pellet the reaction rate increases markedly and the rivet is consumed or weakened to

the point that member 3 breaks away.

The basic device can be tailored for a broad range of applications and time delay periods. The water vapor permeability properties of membrane 6, membrane thickness, and membrane area, provide one set of design variables which tailor the time delay period. The width of the airgap between the pellet and rivet head provides another time delay design variable. The size of the rivet head affects the time required for it to be consumed to release member 3.

- 10 The storage environment may consist of a simple, sealed, impermeable, bag or container and an adequate amount of desiccant. It is also possible, depending on pellet formulation, to store the timer in a frozen state with the unit "coming to life" after thawing, or to store the timer in a moist or wet environment with the chemical action occurring as the timer dries out.

- 15 Inasmuch as the time delay action results from a water or vapor induction period, followed by a gas phase chemical reaction, and then a liquid phase chemical reaction, the effect 20 of variations in environmental humidity level on the time delay period is reduced.

- 25 To give examples of materials which may be used, the pellet may consist of a suitable corrosive salt, e.g. cupric chloride, ferric chloride, etc., with inert fillers such as silica flour to insure pellet integrity and to provide adequate granular surface area, water soluble binders, and desiccant additives.

I claim:

1. Chemical-mechanical timer apparatus comprising a body member, a mechanical coupling member, a securing device 30 having a portion adapted to be chemically attacked securing said coupling member to said body member, means to weaken said securing device during a period of time to permit separation of said body member and said coupling member, said means comprising a chemical material adapted to be actuated 35 upon a change of environmental moisture conditions, said chemical material comprising a corrosive salt soluble in said environmental moisture and in proximity to said securing device such that said corrosive salt, upon actuation by environmental moisture, chemically attacks said securing device and weakens same during said period of time, at the end of 40 which said securing device structurally fails and releases said mechanical coupling member.

2. Apparatus as in claim 1 wherein said chemical material further comprises an inert filler and a moisture soluble binder.

3. Apparatus as in claim 2 wherein said chemical material further comprises a desiccant additive.

4. Apparatus as in claim 1 wherein said securing device comprises a rivet with a head adjacent to said corrosive salt.

5. Apparatus as in claim 4 wherein said rivet comprises an 50 aluminum alloy.
